UNITED STATES PATENT OFFICE.

JOHN F. ALLEN, OF ERIE, PENNSYLVANIA, ASSIGNOR OF ONE-THIRD TO J. A. HIM-
ROD AND ONE-THIRD TO EDWARD E. ALLEN, BOTH OF ERIE, PENNSYLVANIA.

RUBBER-MOLDING APPARATUS.

Application filed June 18, 1924. Serial No. 720,872.

To all whom it may concern:

Be it known that I, JOHN F. ALLEN, a citizen of the United States, residing at Erie, in the county of Erie and State of Pennsylvania, have invented new and useful Improvements in Rubber-Molding Apparatus, of which the following is a specification.

This invention is designed to mold rubber articles and is exemplified for making receptacles for storage batteries. Such an apparatus should be arranged for conveniently reloading the mold and conveniently discharging the same without distorting the article.

15 The invention is illustrated in the accompanying drawings as follows:—

Fig. 1 shows a side elevation, partly in section, on the line 1—1 in Fig. 2.

20 Fig. 2 a plan view, partly in section, on the line 2—2 in Fig. 1.

Fig. 3 a side elevation of the head, the view being at right angles from that shown in Fig. 1.

25 1 marks the base, 2 the ram cylinder, 3 the ram, 4 the ram cap, 5 the press head, and 6 rods connecting the base and head. These are of usual construction.

30 A mold case 7 is arranged on the ram cap. This is steam-heated, the steam being admitted to the ram cap through openings 8 and the mold casing having steam cavities 9 connected with the openings 8. This mold case forms a box open at the top and on the ordinary press there would be a plurality of these boxes as shown.

35 A mold lining is arranged within the box and comprises the bottom 10, the sides 11 and ends 12, the sides and ends being superimposed upon the bottom and preferably set 40 into a groove 13 in the bottom so as to hold them initially in place. With this arrangement of mold lining the mold lining may be stripped out of the case by pressure exerted on the bottom.

45 A knock-out pin 14 extends through openings 15 in the ram cap. These have heads which are arranged in sockets under the bottoms of the mold lining. Slides 17 are mounted in guides 18 in the base, the slides being adapted to be moved inwardly so as to be in the path of the knock-out pins 14. As the ram is lifted to complete a mold and held in lifted position so as to

subject the molding rubber to pressure during the molding operation the slides 17 are 55 moved inwardly so that as the ram cap returns under pressure by means hereinafter described the mold linings are forced out of the mold casings.

In order that the slides 17 may be worked 60 together I preferably provide the levers 19 which have the pivots 20 on the base. Links 21 connect these levers with a rock arm 22 so that both slides may be thrown simultaneously.

65 In order to force the ram downwardly so as to assure the stripping of the mold lining I provide the following mechanism: A hollow rod 23 is secured to the mold casing and connected with the cavity 9. It extends 70 through an opening 23^a in the head 5 and is secured to a piston 24. The piston operates in a cylinder 25. Steam is admitted to the cylinder through an opening 26. Steam remains on the piston constantly so that 75 there is a sufficient pressure to force the ram downwardly to affect the stripping of the mold lining. Further steam is delivered in this way to the mold casing and ram cap.

80 The mold is made up of sections 27 and 28, the receptacle or battery box being formed with the mold exemplifying the invention having three compartments. The end sections 27 are formed rigid with the head 85 while the central section 28 is preferably mounted on pins 29, the pins having heads 30 arranged in sockets 31 in the press head 5. This permits a limited movement of the central section 28 as the ram is retracted, 90 thus separating the cores from the sections 27 prior to the separation of the section 28. This reduces the strain on the formed article and is less liable to result in a distortion of the article as the core is removed.

95 While I have shown the mold provided with overhanging or crosswise extending shoulders engaging the walls of the molded article thus holding the molded article in the mold during the retraction of the mold and consequent stripping of the cores from the receptacle I have not claimed this feature in the present application, this forming the subject matter of a companion application, Serial Number 43,118, filed July 13, 1925. 100 What I claim as new is:—

1. In a rubber molding apparatus, the combination of a mold; a ram carrying the mold; a head closing the ram; a steam cylinder on the head; a piston in the cylinder; and a hollow piston rod extending from the piston to the ram conveying steam to the mold.
2. In a rubber molding apparatus, the combination of a mold; a ram carrying the mold; a head opposing the ram; a mold core mounted on the head; a fluid cylinder mounted on the head; a piston in the cylinder; and a rod extending against the ram to force a return movement of the ram to force the mold from the core.
3. In a rubber molding apparatus, the combination of a ram; a mold on the ram; a knock-out device operating to discharge the mold on a backward movement of the ram; and means forcing a backward movement of the ram comprising a cylinder on the head, a piston in the cylinder, and means for communicating the movement of the piston to the ram.
4. In a rubber molding apparatus, the combination of a ram; a mold case on the ram; means for subjecting the mold case to a vulcanizing heat; a separable mold lining in the case; and a knock-out acting on a backward movement of the ram on the mold lining to discharge it from the case.
5. In a rubber molding apparatus, the combination of a mold case; means for subjecting the case to vulcanizing heat; a separable mold lining in the case; a mold core completing the interior of the mold within the case; fluid-actuated means forcing the core into the case to fill the mold with material and holding the parts under pressure during the vulcanizing action and for first disengaging the core from the mold and means associated therewith then disengaging the lining from the case.
6. In a rubber molding apparatus, the combination of a ram; a mold case on the ram; a separable mold lining in the case; a knock-out acting on the mold lining to discharge it from the case actuated by a movement of the ram; and means mounted on the head forcing a backward movement of the ram.
7. In a rubber molding apparatus, the combination of a ram; a mold case mounted on the ram; a separable mold lining arranged in the case comprising a bottom and superimposed separable sides and ends; a knock-out pin mounted in the ram; and means movable in the path of the pin for discharging the lining.
8. In a rubber molding apparatus, the combination of a ram; a plurality of mold casings on the ram; mold linings arranged in the casings; knock-out pins arranged under the linings; knock-out means adapted to be moved in the path of the pins; and a common device for actuating said means simultaneously.
9. In a rubber molding apparatus, the combination of a ram; a head opposed to the ram; a mold mounted on the ram; a mold core carried by the head; and means mounted on the head for forcing a backward movement of the ram to disengage the mold from the core.
10. In a rubber molding apparatus, the combination of a ram; a head opposed to the ram; a mold mounted on the ram; and a core mounted on the head, said core having a plurality of sections, one of the sections being movably mounted making the parting of the sections from the mold successive.
11. In a rubber molding apparatus, the combination of a ram; a head opposed to the ram; a mold mounted on the ram; and a core mounted on the head, said core having a plurality of sections, one of the sections being movably mounted making the parting of the sections from the mold successive comprising headed pins extending from the movable section into the head.
12. In a rubber molding apparatus, the combination of a mold; a separable lining in the mold; a mold core; power actuated mechanism forcing relative movement between the mold lining and core; means associated with the mechanism causing movement between the lining and the mold, and means subjecting the mold to vulcanizing heat.
13. In a rubber molding apparatus, the combination of a mold; a separable mold lining in the mold; a mold core; power actuated mechanism exerting molding pressure on the mold; power actuated apparatus comprising pressure devices separating the lining and the core and means associated therewith causing a power forced separation of the mold and lining.
14. In a rubber molding apparatus, the combination of a mold; a separable mold lining in the mold; a mold core; power actuated mechanism exerting molding pressure on the mold; power actuated apparatus comprising pressure devices separating the lining and the core; means associated therewith causing a power forced separation of the mold and lining; and means subjecting the mold to vulcanizing heat.
15. In a rubber molding apparatus, the combination of a mold; a separable mold lining; a mold core; power actuating mechanism forcing the core and mold together to force a flow of inserted rubber to mold cavity form; power actuating apparatus comprising devices separating the core and lining and means associated therewith causing a power forced separation of the mold and lining.
16. In a rubber molding apparatus, the

combination of a mold; a separable mold lining; a mold core; power actuating mechanism forcing the core and mold together to force a flow of inserted rubber to 5 mold cavity form; power actuating apparatus comprising devices separating the core and lining; means associated therewith caus-

ing a power forced separation of the mold and lining; and means subjecting the mold to vulcanizing heat.

In testimony whereof I have hereunto set my hand.

10

JOHN F. ALLEN.
